Primary Examiner — Katie Jane Stofko(74) Attorney, Agent, or Firm — Cionca IP Law P.C.;
Marin Cionca(57) CLAIM

The ornamental design for a packet, as shown and described.

DESCRIPTION

FIG. 1 is a perspective view of a packet showing the new design;

FIG. 2 is a front elevation view thereof;

FIG. 3 is a rear elevation view thereof;

FIG. 4 is a top view thereof;

FIG. 5 is a bottom view thereof;

FIG. 6 is a left side view thereof;

FIG. 7 is a right side view thereof; and,

FIG. 8 is a perspective view of the packet in a folded state while in use.

The broken lines shown in FIGS. 1–7 illustrate portions of the packet that form no part of the claimed design. The broken lines illustrating the mug and the hand in FIG. 8 are environment, while the remaining broken lines in FIG. 8 illustrate portions of the packet that form no part of the claimed design.
